UNITED STATES PATENT OFFICE.

ERNEST E. CURRIER, OF IPSWICH, MASSACHUSETTS.

AUXILIARY SUBLUING-REFLECTOR FOR HEADLIGHTS.

1,381,404.

Specification of Letters Patent. Patented June 14, 1921.

Application filed October 14, 1919. Serial No. 330,557.

To all whom it may concern:

Be it known that I, ERNEST E. CURRIER, citizen of the United States, residing at Ipswich, in the county of Essex and State 5 of Massachusetts, have invented certain new and useful Improvements in Auxiliary Subduing-Reflectors for Headlights, of which the following is a specification.

This invention relates to motor vehicle or 10 other electric headlights and has as one of its principal objects to provide means which will eliminate the otherwise blinding effect of the headlights upon pedestrians or other persons approaching along a roadway.

15 The invention has as a further object to provide a screen or interceptor adapted to be mounted within a headlight in such manner as to throw rays of colored light across the stream of light reflected by the headlight 20 thereby subduing the said stream of light.

And the invention has as a still further object to provide a screen or interceptor which will be exceedingly simple in its construction and which may be readily employed in connection with substantially any conventional type of motor vehicle headlight without the necessity for structural change 25 therein.

Other and incidental objects will appear 30 hereinafter.

In the drawings:

Figure 1 is a vertical sectional view showing a conventional type of motor vehicle headlight equipped with my invention.

35 Fig. 2 is a perspective view showing the screen in detail.

Fig. 3 is a view similar to Fig. 1 showing a slightly different form of screen.

In order that the construction, mounting 40 and operation of my improved device may be accurately understood I have, in the drawings, shown the device in connection with a motor vehicle headlight 10. This headlight is equipped with the usual parabolic reflector 11 and is closed at its front end by a front pane 12. Entering through the back of the headlight casing into the reflector is a lamp socket 13 carrying a lamp 14, the lamp being formed with the usual 45 stem or base removably engaged in the forward end of the socket. As is well known, the ordinary headlight of this type projects a very strong stream of light producing a pronounced blinding effect upon persons 50 whose vision is directed toward the headlight. The present invention seeks to pro-

vide a simple and inexpensive device for overcoming this obnoxious feature; thereby making it unnecessary to employ a separate front pane for the headlight or resort to 60 coating or coloring said pane for subduing the light.

In carrying my invention into effect, I employ a substantially segmental shaped plate or body 15 provided at its inner end with a 65 reduced attaching shank 16 which is formed with an angularly disposed eye 17. As will be observed, the body is formed along the lines of a parabola, being curved or concaved both longitudinally and transversely from 70 the base of the eye 17.

The interceptor or screen may be of any suitable material and its inner concave face is coated with a distinctive color such as red, blue, green, yellow or any other desired tint. If the interceptor is formed from material originally of a plastic nature, such as celluloid or glass, the material itself may be impregnated with the coloring matter. 75

In Fig. 1 of the drawings, I have shown 80 my improved device mounted within the headlight 10. As shown therein the eye 17 of the screen or interceptor is of a size to snugly receive the stem or the base of the lamp therethrough. Consequently, by first 85 removing the lamp from the socket 13 and then fitting the stem of the lamp through said eye, the device will, when the lamp is again engaged with its socket, be properly supported by the lamp stem within the 90 headlight. I accordingly provide a device which may be readily employed in connection with any conventional type of headlight without necessitating any structural change therein. 95

Fig. 3 of the drawing shows a screen 15' which is given a longitudinal curvature approximately concentric with the headlight reflector, whereas in Fig. 1 the screen 15 is somewhat eccentric to the reflector and is 100 spaced slightly farther therefrom at its front free end than at its rear end. In both cases, however, the screen conforms generally to the curvature of the reflector.

The blinding glare from high power headlights is due to the fact that the rays of light striking the forward portion of the bottom section of the reflector are directed upwardly so that they strike the eyes of a person looking at the headlight instead of 105 being thrown onto the surface of the ground. By the use of my device, all these rays are 110

intercepted and partake of the color of the screen, so that while sufficient strong white light is thrown out from the upper portion of the reflector and projected directly forward from the lamp to illuminate the path ahead, the colored rays which are directed upwardly will so modify and subdue the strong white light from the upper portion of the reflector that all glare is eliminated.

10 To facilitate an understanding of the action, I have illustrated the general course of the rays issuing from the lower portion of the lamp in a conventional manner in Fig. 1. My interceptor is preferably of translucent

15 cent material and the rays of light pass through the same to the reflector, as indicated, the result being that all rays projected from the lower portion of the reflector will be modified and softened by the color

20 of the interceptor. The interceptor will also serve to diffuse the light rays passing to and through the same and any portions of the light which may be reflected from the upper surface of the interceptor will be colored and

25 will follow paths having the same general directions as those indicated so that an opaque colored interceptor may be used with good results, although greater diffusion of the light and better illumination of the road

30 will be obtained with a translucent interceptor. It will also be noted that the interceptor projects forwardly to such an extent that rays of light passing downwardly from the lamp and escaping the front end of the

interceptor will also escape the front edge 35 of the reflector but its side edges are sufficiently below the lamp to permit uninterrupted escape of the light passing directly forward from the lamp or horizontally therefrom in lateral directions so that while 40 it does not interfere with the rays passing straight ahead nor with those directed onto the road all the rays which are diverted upwardly are softened and modified by the color of the interceptor and the glare is thus 45 eliminated.

Having thus described the invention, what is claimed as new is:

In a headlight, the combination with a reflector, and a lamp disposed in front of the reflector, of a colored screen consisting of a segmental plate arranged between the lower portion of the lamp and the lower portion of the reflector, the side edges of the screen being below the axis of the lamp and of the 50 reflector and the front end of the screen being in advance of the lamp and below the axis of the same, the side edges of the screen converging rearwardly and the screen terminating at its rear end in an upturned eye 55 adapted to engage around the stem of the lamp whereby to support the screen, the screen conforming generally to the curvature of the reflector whereby throughout its area it will be spaced from the reflector. 60

65 In testimony whereof I affix my signature.

ERNEST E. CURRIER. [L. S.]
